F. J. MILLER.

PUMP.

FILED APR. 13, 1922.

F. J. MILLER, Inventor

By

Jesse P. Stone

his Attorney

UNITED STATES PATENT OFFICE.

FRANK J. MILLER, OF LOS ANGELES, CALIFORNIA, ASSIGNOR TO SANDERS WALKER,
OF WICHITA FALLS, TEXAS.

PUMP.

Application filed April 13, 1922. Serial No. 552,257.

To all whom it may concern:

Be it known that I, FRANK J. MILLER, a citizen of the United States, residing at Los Angeles, Los Angeles County, California, have invented a certain new and useful Improvement in Pumps, of which the following is a full, clear, and exact description, such as will enable others skilled in the art to which it appertains to make and use the same.

10 My invention relates to an improvement in deep well pumps and is designed especially for working in oil and water wells of great depth, wherein quantities of sand and other sediment is contained in the oil, tending to wear the plunger and pump barrel.

15 It is the object of my invention to provide a pump which will wear for a long period of time and still maintain efficiency.

Another object is to provide a means of 20 disposing of the sand ordinarily tending to settle about the plunger and working barrel so that it will not wear the pump or clog the working of the valves.

Other objects and advantages will be 25 apparent to one skilled in the art upon the more detailed description which follows:

Referring to the drawing wherein the preferred embodiment of my invention is set forth, I have shown a central longitudinal 30 section through a tubing or pump barrel equipped with my invention.

In the drawing the tubing or pump barrel is shown at 1. At one of the joints adjacent the lower end of this tubing I provide a disk 35 or diaphragm 2, which is threaded on its outer periphery to screw within the adjacent ends of the two joints in the tubing 1. This diaphragm is of substantial thickness and is countersunk and threaded at 3 on its upper 40 surface to provide a stuffing box of ordinary construction.

Working within this stuffing box is a tubular plunger 4. This plunger has at its upper end a ball cage or crown 5, a valve 45 seat 6, and a ball valve 7. The plunger is adapted to work fluid-tight through the stuffing box and to extend downwardly into the tubing, telescoping within an upstanding pipe or stationary plunger 8, secured adjacent the foot valve.

At a point spaced somewhat above the upper end of the stationary pipe 8 I provide a coupling 9 on the outer surface of my plun-

ger, this coupling being threaded on both its outer and inner surfaces. It acts to connect the two portions of the plunger and also for attachment on its outer surface to an outer plunger 10. This outer plunger is spaced from the inner plunger 4 sufficiently to include the stationary pipe 8, and to telescope closely over the outer surface of said pipe.

The stationary pipe or plunger 8 is secured within a threaded opening 11 within a perforated diaphragm 12, fixed on the inner facing of the tubing 1. The said diaphragm or disk 12 is perforated by means of openings or holes, 13, to allow the passage downwardly therethrough, of sand accumulating within the pump barrel. The diaphragm 12 has a downwardly extending projection or flange 14 threaded on its outer face for attachment within a coupling 15.

Below the end of this flange is fixed a foot valve 16 secured within the coupling 15 and closing the passage through the tubing coupling except for a central valve-closed opening 17. The foot valve 18 fitting within the said opening 17 is preferably tapered downwardly to form a close fit therein. Below 50 the foot valve 16 is a downwardly extending pipe 19 which forms a housing between which and the tubing is a sand chamber 20. Within the pipe 19 and extending downwardly from the foot valve is an inner oil 55 suction pipe or gas anchor 21, of ordinary construction.

In the operation of my device, the diaphragm 2 through which the plunger reciprocates, forms a sand-catcher, tending to 60 eliminate the falling of the sand down around the plunger. The plunger works through the stuffing box, and sand settling from the oil being pumped will be prevented from working past the stuffing box to the 65 plunger. Should the stuffing box become worn however, and sand find its way downwardly around the plunger, such sand would fall upon the lower disk 12 and be carried through the openings 13 therein, to the 70 chamber 20 toward the bottom of the well.

The plunger formed by the two concentric pipes 4 and 10 telescoping over the stationary pipe 8 in the manner shown and described, results in a type of piston which 75 will not readily wear, and even when worn,

will tend to maintain a complete suction. This will be due to the fact that an oil film will form between the telescoping pipes and serve to maintain the same air-tight even after they have become quite worn.

The advantages of this type of pump will be apparent to one skilled in the art. The sand will be prevented from obtaining entrance down around the plunger, due to my 10 sand catcher, but even if sand does obtain entrance about the plunger to some extent, the particular construction of the said plunger will prevent the reciprocating parts from leaking for long periods of time, due 15 to the manner in which the oil assists in forming a tight closure between the reciprocating parts.

Having thus described my invention, what I claim is new and desire to protect by Letters Patent is:

1. In a pump, a pump barrel, a transverse diaphragm across said pump barrel, and a stuffing box therein, a plunger reciprocating through said stuffing box, a foot valve, an 25 upwardly extending pipe secured thereto, said plunger formed to telescope both outside and inside said pipe, and storage means for sand forming about said plunger.

2. In a pump, a pump barrel, a diaphragm 30 closing the passage therethrough and a plunger fitting tightly through an opening in said diaphragm and adapted to reciprocate therethrough, an outer concentric pipe secured to said plunger below said diaphragm, a foot valve below said plunger, a 35 pipe projecting upwardly from said foot valve and adapted to telescope between said

concentric pipes forming said plunger, in the manner described.

3. In a pump, a pump barrel, a plunger 40 therein comprising a central tubular member, and valve-controlled passage therethrough, an outer tubular member secured thereto and spaced upwardly therethrough, a foot valve, an upwardly projecting pipe 45 secured thereto and adapted to fit between the outer and inner pipes comprising said plunger, and means to prevent the sand from settling about said plunger and said foot valve.

4. In a pump, a pump barrel, a foot valve 50 therein, a perforated diaphragm, a pipe secured therein, a valve-closed opening below said pipe, a plunger telescoping over said pipe, and means to prevent sand from accumulating about said plunger comprising an upper diaphragm through which said plunger reciprocates.

5. In a pump, a pump plunger comprising 55 an inner tubular member having a valve-controlled opening therethrough and spacing member thereon, an outer tubular member secured to said spacing member, a lower perforated diaphragm, a pipe secured in said lower diaphragm, said plunger telescoping over the upper end of said pipe, and a chamber formed below said perforated diaphragm to receive sand tending to accumulate around said plunger.

In testimony whereof, I hereunto affix my 70 signature, this the 27th day of March, A. D. 1922.

FRANK J. MILLER.
